UNITED STATES PATENT OFFICE

119,039

DESIGN FOR A UTENSIL SUPPORT FOR A DOMESTIC RANGE

John F. Hennessy, Rockford, Ill., assignor to Geo. D. Roper Corporation, Rockford, Ill., a corporation of Illinois

Application December 7, 1939, Serial No. 88,748

Term of patent 7 years

To all whom it may concern:

Be it known that I, John F. Hennessy, a citizen of the United States, residing at Rockford, in the county of Winnebago and State of Illinois, have invented a new, original, and ornamental Design for a Utensil Support for a Domestic Range, of which the following is a specification, reference being had to the accompanying drawing, forming part thereof.

In the drawing:

Fig. 2 is a plan view thereof.

I claim:

The ornamental design for a utensil support for a domestic range, substantially as shown.

JOHN F. HENNESSY.
